UNITED STATES PATENT OFFICE.

FREDERICK WILLIAM NUNN, OF GUILDFORD, NEW SOUTH WALES,
AUSTRALIA.

DEVICE FOR EXHIBITING HATS, BONNETS, AND THE LIKE.

No. 845,569.

Specification of Letters Patent.

Patented Feb. 26, 1907.

Application filed March 8, 1906. Serial No. 304,916.

To all whom it may concern:

Be it known that I, FREDERICK WILLIAM NUNN, a subject of the King of Great Britain and Ireland, residing at Guildford, in the State 5 of New South Wales, in the Commonwealth of Australia, have invented a new and useful Device for Exhibiting Hats, Bonnets, and the Like, of which the following is a specification.

10 This invention relates to an adjustable device for displaying hats, bonnets, and the like in shop-windows and show-rooms.

The object of the invention is to provide a device for this purpose on which the article 15 to be displayed can be quickly and firmly fastened and also readily removed, while the device can be easily and quickly changed from an upright to an inverted position or placed at any angle in order to show the article to its best advantage, according to its 20 position in a show-room or shop-window.

My device consists mainly of a spring-frame constructed so as to grip the hat firmly inside the crown. This frame, which 25 is made of a double strand of wire and held together at suitable points by solder, binding-wire, or in any suitable manner, forms at the lower part a double spring-loop, which loops fit on a flat plate or disk, one on either 30 side. This plate or disk is provided with two pins projecting at both sides. These pins are placed obliquely one above the other, so that the upper pin will be inside and the 35 lower one outside the wire loop, which arrangement permits the frame to be placed in any desired position or angle, as through its own weight the loop will be firmly caught and held between the pins. The plate or disk carrying the frame is mounted on a 40 socket which can be placed on any ordinary upright stand or wall-bracket; but in order that my invention may be properly understood I will now refer to the drawings accompanying and forming part of this complete 45 specification, in which—

Figure 1 is a side elevation of the complete device mounted on a wall-bracket. Fig. 2 is a front elevation, and Fig. 3 is a plan, of the same. Fig. 4 is a front elevation of the

spring-frame. Fig. 5 is a side elevation of 50 the supporting-plate and socket. Fig. 6 is a front elevation of same.

The independent half-hoops *a* and *a'*, preferably made of steel wire, together with the arc-shaped radial wires *b* and *b'*, form the 55 frame on which the hat, bonnet, or the like is to be mounted. The wires *c* and *c'*, connected to the half-hoops *a* and *a'*, respectively, 60 form at their lower end the spring-loop *d*, and being double are slipped over a plate or disk *e*, provided with the projecting pins *f* and *f'*, and attached to a socket *g*, which socket in its turn may be mounted on a wall-bracket *h*, as shown in the drawings, or on any other 65 suitable stand.

In order to fasten a hat or other article onto the frame, the spring-loop *d* is slightly compressed, thereby bringing the half-hoops *a* and *a'* sufficiently close together for inserting them into the crown of the hat, and when 70 the spring is released these half-hoops *a* and *a'* will hold the hat firmly in place. By moving the spring-loop *d* round between the pins the hat may then be given any desired 75 position, while the socket allows the whole to be turned round or to be taken off entirely in order to show the hat to a customer.

I do not confine myself to the method of construction of the spring-frame and the carrying plate or disk as shown in the drawings. 80

What I claim, and desire to secure by Letters Patent, is—

1. A device of the class described, comprising a frame for engaging the interior of a hat, a socket-piece having a plate provided with 85 pins projecting upon opposite sides thereof, one of said pins being above and in advance of the other, and loops connected with the frame and adapted to engage between the pins on opposite sides of the plate. 90

2. A device of the class described, comprising a frame composed of a plurality of sections for engaging the interior of a hat, a socket-piece having a plate provided with pins projecting upon opposite sides thereof, 95 and a loop connected with each section, and adapted to engage between the pins on the adjacent side of the plate.

3. A device of the class described, comprising a frame for engaging the interior of a hat, a socket-piece having a plate provided with pins projecting upon opposite sides thereof, and loops connected with the frame and adapted to engage between the pins on opposite sides of the plate.

In testimony whereof I affix my signature in presence of two witnesses.

FREDERICK WILLIAM NUNN.
